Atty:

UNITED STATES PATENT OFFICE.

HOWARD A. REDFIELD, OF MONTEREY PARK, CALIFORNIA.

KEEPER FOR CUFF BUTTONS.

Application filed February 2, 1925. Serial No. 6,168.

To all whom it may concern:

Be it known that I, HOWARD A. REDFIELD, a citizen of the United States of America, and a resident of Monterey Park, in the county of Los Angeles and State of California, have invented certain new and useful Improvements in Keepers for Cuff Buttons, set forth in the annexed specification.

My invention is a keeper for cuff buttons, and has for its object the production of a simple and efficient device for preventing the loss of cuff buttons in case the lesser or folding head of the button slips thru the button hole of the cuff.

15 In the accompanying drawings

Fig. 1 is a plan at an enlarged scale of a keeper in the form of a wheel;

Fig. 2 is a central vertical section;

Fig. 3 is a central horizontal section;

20 Fig. 4 is a section on line 4—4 of Fig. 1; and

Figs. 5 and 6 show two ways of applying the keeper to a cuff button located in a cuff.

25 The keeper is in the form of a plate of soft rubber or equivalent material. This plate may be of any convenient form, but I have illustrated it as a disk having a heavy edge or rim 10 and a thin web 11. The rim is for stiffening purposes.

30 At the center is a hub 12 having a central opening 13. From the hub to the rim are two arms 14, and in these arms are slots 15 running from the opening 13 to openings 16 near the rim. I have also shown two other arms corresponding to arms 14, and perpendicular thereto, but these are matters of symmetry.

40 The total length of the slotted portion, from one hole 16 to the other, is preferably a little less than the length of a button hole in a cuff, and the total diameter of the keeper is greater than the button hole length. The material around the holes 16, particularly

at the edges of those holes furthest from the center 13, is made heavier than elsewhere. This is for reinforcement to overcome a tendency to tear at this point when placing the keeper on or removing it from a cuff button. Making the holes 16 of a diameter considerably greater than the width of the slots 15 also reduces the tendency to tear at the ends of the slots.

The two slots 15 are in fact one slot having a central enlargement 13, and terminating in enlargements 16. The material around the slot is reinforced, this reinforcement being slightly greater at the ends of the slot than elsewhere.

In Fig. 5 I have shown the keeper mounted on the shank 17 of a cuff button, and between the edges of the cuff 18. In Fig. 6 I have shown it located between the folds of the cuff and adjacent to the lesser head of the button. If the head 19 should slip thru the button hole in the cuff, as very commonly happens, it would be retained by the keeper because the keeper is of resilient material and maintains its position in intimate contact with the shank of the button. It is to be noted that in either position, the keeper is concealed by the material of the cuff.

What I claim is:

1. A cuff button keeper composed of soft rubber molded into the form of a disk having a reinforced rim and provided with a transverse slot, the material around the slot being also reinforced.

2. A cuff button keeper composed of soft rubber molded into the form of a plate having a reinforced outer edge and provided with a transverse slot, said slot having its ends terminating in round holes of a diameter greater than the width of the slot, the material adjacent to the slot and around the holes being reinforced.

HOWARD A. REDFIELD.
